UNITED STATES PATENT OFFICE

WILLIAM M. BAXTER, OF LOUISVILLE, KENTUCKY, ASSIGNOR TO ESKIMO PIE CORPORATION, OF LOUISVILLE, KENTUCKY, A CORPORATION OF DELAWARE

VENDING MACHINE

Application filed July 16, 1927. Serial No. 206,221.

This invention relates to vending machines and more particularly to refrigerated ice cream vending devices, although it may be employed with equal advantage for other purpose.

5 It contemplates more especially the provision of means of increased capacity for enabling the dispensation of vendible articles responsive to the deposition of a coin of predetermined value.

10 Numerous vending devices have heretofore been proposed, but these have not proven entirely satisfactory in that their capacity is much to limited for dispensing unstable articles such as normally liquid substances frozen to a substantially solid state. In view thereof, frequent replenishment of the vendible supply is not practical from a commercial standpoint, nor thermally efficacious due to the increased thermal transmission occasioned by subjecting the refrigerated interior thereof to the effects of the surrounding atmosphere.

15 One object of the present invention is to simplify the construction and improve the operation of devices of the character mentioned.

20 Another object is the provision of a vending machine which is inexpensive and dependable in operation.

25 Still another object is to provide a refrigerated vending machine of increased capacity to enable the dispensation of unstable vendible articles.

30 A further object is to provide means for the reception of a series of stacked vendible articles which are consecutively dispensed in sequence.

35 A still further object is the provision of a carrier having a plurality of article magazines therein for selective association with a coin dispenser to effect their ejection in automatic sequence.

40 Still a further object is the provision of a rotatable carrier capable of supporting a plurality of magazines for individually subjecting the articles therein to enable dispensation in sequence responsive to the deposition of a coin.

45 Other objects and advantages will appear

from the following description of an illustrative embodiment of the present invention.

In the drawings:

Figure 1 is a fragmentary sectional view in elevation of a device embodying features 55 of the present invention;

Figure 2 is a sectional view in elevation of a self-contained refrigerated cabinet for confining the instrumentalities disclosed in Figure 1;

Figure 3 is a perspective view in elevation of an article confining mechanism employed in connection with the illustrated invention;

Figure 4 is a fragmentary sectional view in plan taken substantially along line 65 IV-IV of Figure 1;

Figure 5 is a sectional view taken substantially along line V-V of Figure 1;

Figure 6 is an enlarged fragmentary view in elevation of the coin ejecting mechanism 70 disclosed in Figure 1;

Figure 7 is a sectional view taken substantially along line VII-VII of Figure 6;

Figure 8 is a fragmentary perspective view of the carrier disclosed in Figure 1; and

Figure 9 is a perspective view of a dummy article employed in connection with each of the magazines.

The structure selected for illustration comprises a casing 10 of any suitable configuration, it being preferably polygonal in contour so as to enable its disposition in any convenient position within the view of the purchasing public. As shown, the casing is divided into two compartments 11 and 12 85 constituting the evaporator and condensing unit confining medium. In view thereof, the compartment 11 is provided with an evaporator 13 consisting of a plurality of vertically disposed tubes which are in communication with spaced circular tubular rings 14 and 15 so as to establish circulation therethrough.

A liquid refrigerant such as methyl chloride is supplied through a pipe 16 which is 95 in communication with an expansion valve 17 connected to the evaporator tubes by virtue of the tube 18 secured thereto in any suitable manner. It is to be noted that the coils 13 are shaped to correspond with the interior 100

of the compartment 11 so that the vendible articles may be confined therein in proximity thereto to receive the effects of thermal heat transmission to the refrigerant simultaneous with its expansion within the coils, thereby 5 maintaining the compartment 11 at a frigid temperature so that vendible articles of unstable character may be maintained therein for extended periods without deterioration.

For this purpose, the walls of the container 10 are provided with insulation 19 so as to decrease the thermal transmission and conduction through the walls with a view of requiring as little refrigeration within the compartment 11 to maintain it at its desired 10 temperature. The top of the cabinet 10 is provided with a closure 20 which preferably has a conical exterior surface 21 with an electric bulb 22 or other advertising fixture disposed at the apex thereof. The closure 15 20 is shaped to correspond with the contour of the cabinet 10 so as to impart a distinctive ornamental appearance thereto, it being removable to enable the evaporator and the other instrumentalities to be introduced 25 within the compartment 11.

The tube 16 terminates in a base 23 confined within the compartment 12, the base 23 carrying a receiver 24 therebeneath in communication with the tube 16 to supply 30 a refrigerant thereto. The receiver 24 is connected with condenser coils 25 arranged in spaced relation to receive a compressor 26 therebetween which creates the flow of 35 the refrigerant thereto through the conduit 27, the low side 28 of the compressor 26 being connected to the pipe 15 of the evaporator 13 by means of a tube 29 so as to effect a continuous cycle constituting the compression, expansion, and return of the refrigerant to the compressor during which 40 time the compartment 11 is refrigerated.

The compressor is driven by a motor 30 supported by the base 23 so that the armature pulley 31 thereof is in aligned relation 45 with the fly wheel 32 serving as a blower for ventilating the compartment 12 and cooling the condenser coil 25 disposed adjacent thereto. As shown, the walls of the compartment 12 are provided with elongated openings 33 having meshed material 34 disposed thereover to enable the transmission of air therethrough. A polygonal side 35 constituting a confining wall of the compartment 12 is hingedly associated with the cabinet 10 so as to permit the introduction of a condensing unit therethrough as well as render it accessible for repairs.

Vendible articles are maintained in the compartment 11 in a prearranged position to enable the selective ejection thereof responsive to the deposition of a coin in the manner to be described hereinafter, it being particularly desirable to provide means affording a large capacity so that the supply

will not have to be replenished repeatedly, which certainly is not advantageous from a commercial standpoint nor thermally efficacious due to the fact that the interior 11 necessarily must be subjected to the direct exposure of the atmosphere during such periods. In view thereof, the present invention contemplates the provision of a bracket 36 which terminates in a vertically extending, axially disposed standard 37 confined 70 within the compartment 11, the base 36 being fixed to the partition wall 38 by virtue of suitable fasteners such as the carriage bolts 39.

A collar 40 is fixed to the extremity of the standard 37, it having radially disposed bosses 41 formed integral therewith to enable the secural of rods 42 thereto owing to the threaded extremities 45 thereof which are in threaded engagement with the bosses 41 for adjustable connection therewith by means of lock nuts 44. It is to be noted that the extremities of the rods 42 are provided with arcuate clamps 45 which engage the tube 14 for the purpose of supporting the evaporator 13 in the desired position within the compartment 11.

Another collar 46 is secured to the standard 37 intermediate the ends thereof by means of a set screw 47 of standard construction, the collar 46 terminating in a peripheral flange 48 spaced from the standard 37 to define a lubricant receiving receptacle for a purpose which will hereinafter be more fully apparent. An annular groove 49 is provided in the collar 46 to receive a ball bearing raceway 50 of standard construction so as to rotatively support the hub 51 of the pulley 52 which is secured to a tubular shaft 53 journaled about the standard 37 to carry a plate 54 formed integral therewith.

The plate 54 is provided with a plurality of radially extending arms 55 which have threaded apertures 56 at their extremities to receive rods 57 depending therefrom to carry another plate 58 in spaced relation to the plate 54 superposed thereabove, the rods 57 terminating in reduced threaded extremities 59 having a nut 60 secured thereto to retain the plate 58 in the desired position. As shown, the plate 58 is provided with an axial circular opening 61 therein so as to co-operate with rollers 62 carried within suitable bushings 63 constituting a part of angularly related brackets 64 which terminate in a collar 65 formed integral therewith in fixed relation with the standard 37. It will be understood that this arrangement enables the rotation of the spaced plates 54 and 58 constituting the vendible article carrier.

A plurality of article confining magazines 66 are detachably associated with the carrier at uniform spaced intervals thereon so as to enable the confinement of a comparatively large number of vendible articles within the

compartment 11. To accomplish this end, the magazines 16 consist of confronting U-shaped plates 67 and 68 which are maintained in spaced relation by virtue of brackets 69 and 70 together with the bottom 71 thereof which sustains the articles thereon. The rear sides 72 of the magazine 66 terminate in the transverse line 73 above the bottom 71 so as to define an opening 74 to permit the ejection of the lowermost article 75 therethrough responsive to horizontal movement imparted thereto from the opposed side.

As shown, the brackets 70 are provided with spaced U-shaped lugs 76 which carry horizontally disposed pins 77 therebetween to engage correspondingly spaced hooks 78 depending from the plate 58 to sustain the magazines 66 in an upright position. The other brackets 69 which are secured to the magazines near the upper ends thereof, are provided with a lug 79 having furcations 80 thereon terminating in cam surfaces 81 which are capable of association with correspondingly shaped projections 82 spaced about the periphery of the plate 54. The plate 54 is provided with flat springs 83 fixed thereto in any appropriate manner so that the free extremities thereof which are provided with arcuate depressions 84 may engage the cam surfaces 81 to retain the magazines in rigid relation with respect to the carrier (Figure 1). Obviously, any number of magazines may be placed about the periphery of the carrier which accommodates ten magazines in the present embodiment. The magazines are preferably detachably associated with the carrier in the manner described hereinabove so that the compartment 11 may be provided with a hinged closure 86 which enables the introduction of the magazines for the purpose of replenishing the supply of the articles.

It is desired to dispense the articles responsive to the deposition of a coin so that it will be unnecessary to have an attendant serving as a salesman for the purpose of effecting the sale thereof. To this end the cabinet 10 is provided with ejecting means comprising a casing 87 secured to the exterior wall thereof to receive the coin mechanism therein for manipulation by a knob 88. The knob 88 is operatively connected to a lever 89 pivoted near one extremity thereof by means of a pin 90 carried by the coin casing 87. The lever 89 is provided with a slot 91 in one extremity thereof so as to engage a pin 92 carried by a lug 93 depending from a carriage 94 slidably disposed for horizontal movement through a passage 95 provided for that purpose in the casing 10, the carriage 94 being movable in guides 96 to permit its movement along a predetermined path.

As shown, the carriage 94 is provided with

a downwardly projecting flange 97 at the extremity thereof so as to co-act with a magazine 66 disposed in confronting relation therewith so that a confronting article 75 may be dispensed therefrom responsive to the rotation of the knob 88 which will only turn subsequent to introducing a coin of predetermined value within the slot 98 provided for that purpose. It is to be noted that numerous types of coin mechanisms are in general use, and for that reason the precise mechanism for establishing an operable connection between the knob 88 and the lever 89 is not shown, as such may be of standard construction to meet the suitable purpose.

Movement of the carriage 94 inwardly responsive to rotation of the knob 88 subsequent to the deposition of a coin will discharge an article 75 through the opening 74 whereupon it will be deposited on an inclined chute 99 for slidable movement through an orifice 100 which is ordinarily closed by virtue of a flat member 101 pivotally associated therewith by virtue of the usual hinged construction 102, the closure 101 having a knob 90 at the free extremity thereof so as to enable the individual to conveniently remove it from the opening to permit the article to slide therethrough for reception within the trough 104. The trough 104 is preferably provided with a slot 105 therein to enable the individual to grab the article by lifting it with the forefinger.

To enable the dispensation of the articles from succeeding magazines in automatic sequence responsive to the depletion of articles in the preceding magazine, means are provided to effect the intermittent motion of the carrier consisting of the plates 54 and 58. In view thereof, the plate 58 is provided with a series of ratchet teeth 106 disposed in circular formation on the under side thereof so as to engage a pawl 107 pivotally associated with the base 36 by means of a pin 108 which is carried by a lug 109 fixed to the base 36. The pawl 107 has a roller 110 journaled in an arm 111 thereof for normal disposition within the path of the ratchet teeth 106 owing to a weight 112 which is slidably associated with the rod 113 carried by the pawl 107 in such a position as to maintain the pawl at the desired elevation. It is to be noted that there is a tooth 106 for every magazine, it being spaced along the same radial line therewith so that the engagement of the roller 110 with the tooth 106 will normally maintain a magazine in operative relation with the ejecting mechanism constituting the operating station.

The carrier is rotated upon release of the pawl 107 by virtue of a weight 114 which is centrally apertured as at 115 to slide axially of the standard 37, the weight 114 being sustained by tension transmitting ropes 115 which are wound about the pulley 52 in a

5 manner to impart rotation to the shaft 53 which supports the carrier on the bearing 50. The bearing 50 is maintained lubricated at all times owing to the cup 48 which is provided with a supply of lubricant therein, the bearing 50 being immersed therein. The ropes 115 preferably travel over rotatable guides 116 journaled in suitable brackets 117 carried by the cup 48, so that the release of the pawl will cause downward movement of the weight 114 to bring the succeeding magazine to the operating station.

10 In order to effect the release of the pawl when the last article 75 has been dispensed from the magazine, a member or dummy article 118 of metallic construction simulating the contour of a vendible article is provided within the magazine 66 for disposition on the articles 75 confined therein. The member 118 is provided with a laterally projecting lug 119 on the lateral surface thereof to ride within the slot defined by the spaced sides 72 of the magazine, the 15 brackets 69 and 70 thereof being provided with depressions 120 and 121 so as to enable the movement of the lug 119 there-through. It is to be noted that the lower plate 58 is also provided with a depression 20 122 for receiving the depression 121 provided in the brackets 70, thereby serving to prevent relative movement between the magazine and the carrier.

25 As the lug 119 approaches the bottom of the magazine, it engages a lever 123 formed integral with the pawl 107 for disposition in the path of the lug so as to cause pivotal movement of the pawl against the action of the weight 112, so that the roller 110 will 30 be disengaged from the ratchet teeth 106, thereby permitting the carrier to be moved to its next position by virtue of the weight 114 which imparts a turning couple thereto. Thereupon the carrier will move until the 35 roller 110 engages the next tooth, which brings the succeeding magazine in confronting relation with the operating station. When all of the magazines have been depleted of their supply of articles, it is necessary to replenish them. Prior to closing of 40 the cabinet subsequent to replenishing the article supply therein, the carrier should be rotated in a direction counter to the normal tendency of rotation occasioned by the weight 114, thereby elevating it to a position which affords successive rotation thereof responsive to the intermittent motion of the carrier occasioned by the weight 114. Obviously, any other suitable expedient such as 45 a spring may be employed for the purpose of imparting the desired movement to the carrier.

50 Further, during the period of depletion and subsequent replenishment, it is essential 55 or at least highly desirable to render the

ejecting mechanism inoperative so that an individual will be precluded from introducing a coin within the casing 87; otherwise it would be impossible for the individual to receive an article sought to be purchased. With this in view, the member or dummy article 118 is provided with another lug 125 disposed oppositely of the lug 119 so as to engage a member 126 which is pivoted to the carriage 94 of the ejecting mechanism, the member 126 being normally maintained in the path of the lug 125 by virtue of a spring 127 which projects through a loop 128 carried by the carriage 94. The projecting extremity of the spring 127 is provided with a member 129 carrying a lug 130 at its extremity to co-act with a plate rotative with the knob 88, the plate (not shown) being provided with a notch to receive the lug 130 to preclude rotation of the knob 88 when the dummy article 118 is in its lower-most position to pivot the member 126 in a counter clockwise direction (Figure 6). The spring 127 is thereby lifted to effect the engagement of the lug 130 with the plate carried by the knob 88. This prevents rotation thereof so that the ejecting mechanism is rendered inoperative during the time the carrier is moved intermittently to bring the succeeding magazine to the operating station for the purpose of dispensing the articles therefrom responsive to the deposition of a coin.

55 With the arrangement of parts above described, it will be apparent that a novel vending machine has been provided wherein a large quantity of vendible articles are confined for selective dispensation responsive to the deposition of coins in the operating mechanism. The condensing unit refrigerates the chamber 11, thereby maintaining the unstable articles 75 free from deterioration for extended periods.

60 Various changes may be made in the embodiment of the invention herein specifically described without departing from or sacrificing any of the advantages thereof as defined in the appended claim.

I claim:

65 In a device of the character described, a pair of plates, rods for maintaining said plates in spaced relation, spaced hooks projecting from one of said plates, spring means on the other of said plates in aligned relation with said hooks, article confining magazines, and means on said magazines spaced to correspond with said hooks and spring means to enable the detachable connection of said magazines with said plates which constitute a carrier therefor.

115 WILLIAM M. BAXTER.
